UNITED STATES PATENT OFFICE.

ELDA S. DELAMAR, OF DURHAM, NORTH CAROLINA.

RETAINER.

Substitute for application Serial No. 89,976, filed April 8, 1916. This application filed June 18, 1924.
Serial No. 720,874.

To all whom it may concern:

Be it known that I, ELDAD S. DELAMAR, a citizen of the United States, residing at Durham, in the county of Durham and State of North Carolina, have invented new and useful Improvements in Retainers, of which the following is a specification.

This invention relates to necktie holders, and more particularly to a device of this nature which is adapted to be fitted in place, and used to retain a necktie in the proper position during the securing of the collar and the knotting of the tie; said invention is identical with the invention constituting the subject matter of my abandoned application, Serial No. 89,976, filed April 8th 1916 and allowed July 26th 1916.

An object of my invention is to provide a device which may be fitted in place upon a turn-over collar to positively hold a necktie between the flaps of the collar until the tie has been knotted, and may then be removed.

A further object is to so construct the device that it may be fashioned from a single length of strap metal requiring only that the piece be bent and looped to take the proper form, and which may be fitted to and removed from the collar without injury to the fabric or soiling of the collar, and which will prevent straining or tearing of the buttonholes or tabs of the collar.

With the above and other objects in view, my invention consists in certain novel features of construction and combinations of parts which will be hereinafter set forth in connection with the drawings and then more particularly pointed out in the claims.

In the drawings:

40 Figure 1 is a transverse sectional view taken through a collar and tie with the device fitted in place in the operative relation.

Figure 2 is a perspective view of the device detached from the collar.

45 In the construction of the device, a single piece of strap metal is folded and looped so that various portions thereof will lie in substantially parallel planes, and in the shaping of the strip, the body portion 1 is formed to have greater length than the extreme width of the inner flap of the standard collar upon which the device is to be used. This body portion 1 is formed adjacent one end of the strip, and the extreme end is looped over to form the mounting hook 2.

The continued length of the strip is looped upwardly as at 3 to provide the front extension 4 which is disposed to lie in a parallel and spaced-apart relation with respect to the body portion 1, the strip being then 60 looped over as at 5 so that this front extension is of less length than the body portion 1, the folding down of the metal forming the back portion 6 of the tie retaining loop, which is formed by again looping the strip 65 upwardly as at 8, this loop 8 being formed somewhat above the loop 3.

The bill of the hook portion forming the mounting hook 2 is bent slightly inwardly as shown at 9 so that the space between the 70 body portion 1 and the bill is slightly constricted rather than flared. The extreme upper end of the tie retaining loop is folded over as at 10, this being the remaining end of the strip and the looping over of the 75 same forming a smooth end which will protect this end against sinking into the material of the collar when the device is being inserted in the operative positioning and will also protect the fabric of the tie against 80 being snagged or torn by contact with the end of the strip. In the use of the device, the tie is fitted between the portions marked 85 6 and 7 of the drawings, and then the device is placed so that the bill 9 of the mounting hook 2 is in engagement with the inner flap 11 of the collar and by moving the parts endwise upwardly, the front extension 4 will be brought to a position of bearing against 90 the inner side of the flap 11, and the tie 12 95 will be carried up between the inner and outer flaps 11 and 13, the looped end 10 of the tie retaining portion having bearing against the inner side of the outer flap 13 of the collar, and consequently preventing displacement of the tie between this looped portion 10 and the outer flap 13. When the device has been moved to a relation that the bill 9 of the mounting hook portion 2 is 100 above the rolled edge 14 of the collar, the inherent flexibility of the metal will cause the body portion 1 to spring back against the flap 11 so that the bill 9 of the hook will fit over the upper rolled edge 14 of the collar, as the device is drawn downwardly thus 105 mounting the parts in such relation that the tie 12 will be held against movement from the position between the flaps 11 and 13 by the looped portions of the device, and the device itself will be held against downward 110

displacement by the hook 2. With this fitting of the parts, the collar may be placed upon the neck band and buttoned and then the tie may be knotted, the device holding the tie in such a relation that twisting of the same or displacement to become wedged between the flaps of the collar is prevented, and thus permitting the proper adjustment of the tie and knotting of the same without the usual pulling and straining to bring the tie to the proper positioning, thus relieving the strain upon the tie and at the same time very materially reducing the strain placed upon the buttonholes the button tabs of the collar. When the collar has been buttoned in place, the body member 1 is between the inner flap and the neckband of the shirt, and by exerting pressure against the looped formation at 3, the device may be moved upwardly to raise the bill 9 of the mounting hook 2 above the top rolled edge 14 of the collar, after which the body portion 1 may be sprung to move the bill 9 inwardly beyond the plane of the side of the flap 11 and downward pulling action exerted upon the device will cause the bill portion 9 to be carried to a relation that it will bear against the flap 11 and then continue movement in the same direction will withdraw the device from the fitted relation, removing the body portion 1 from between the inner flap 11 and the neckband of the shirt and withdrawing the portions generally indicated at 4, 6, and 7 from between the flaps 11 and 13, the looped formation 10 causing the end of the tie retaining portion to ride between the tie 12 and the outer flap 13 without injury to either of these portions.

From the foregoing it will be seen that I have provided a device which is very simple and inexpensive in its cost and in the construction and manufacture of the same, and which will at the same time very efficiently perform the function for which it is intended, and while I have herein shown and described only one specific form of the device, it will be understood that modifications and variations may be resorted to in the forming and the relative arrangement of the parts without departing from the spirit and scope of my invention, and hence I do not wish to be limited to the exact disclosure but only to such points as may be set forth in the claims.

I claim:

1. A necktie retainer to be fitted to a collar to hold a necktie in place thereon during the knotting of the same and to be subsequently removed which retainer has a portion arranged to be received over the upper edge of the collar to aid in the holding action.

2. A necktie retainer comprising a necktie engaging portion and portions embracing a hook arranged to be received over the upper edge of the collar formed to hold the device upon a collar to retain the necktie in the proper positioning thereon during the knotting of the same and to subsequently permit removal of the device.

3. A necktie retainer comprising a single piece of sheet metal shaped to form a necktie receiving portion adapted to be fitted between the flaps to a turn-over collar and a portion to be fitted to the collar over the upper edge thereof to retain the device in a positioning to hold the necktie in the proper relation until the knotting of the same has been completed after which the device may be removed.

4. A necktie retainer comprising a single strip of sheet metal shaped to provide a body portion having a tie retaining loop disposed at one side thereof, said parts being so arranged that a necktie may be fitted to the tie retaining loop and when the device is fitted in place will be held between the flaps of a turn-over collar, and a portion of said strip shaped to provide a mounting hook to be received over the upper edge of the collar to removably secure the device in place on a collar.

5. A necktie retainer comprising a single strip of sheet metal shaped at one end to provide a mounting hook and having a straight body portion adjacent this mounting hook, the strip looped to form a front extension and then shaped to provide a tie retaining loop, and said portions being so arranged that the device may be fitted to a turn-over collar with a tie in the retaining loop so that the necktie will be held between the outer and inner flaps of the collar and the device will be maintained in place by the mounting hook.

In testimony whereof I affix my signature.

ELDAD S. DELAMAR.
